UNITED STATES PATENT OFFICE.

WILLIAM GRISCOM COXE, OF PHILADELPHIA, PENNSYLVANIA, AND GUSTAV M. LAGERGREN, OF WILMINGTON, DELAWARE; HELEN BAER COXE EXECUTRIX OF SAID WILLIAM GRISCOM COXE, DECEASED.

OIL-INJECTION-CONTROL DEVICE.

Application filed July 29, 1926. Serial No. 125,724.

Our present invention relates to oil injection control devices, and particularly to a periodic oil injection control adapted for use in conjunction with the oil supply to Diesel engines and the like.

An object of this invention is to provide a control device which is fluid actuated and with which the control valve is positively moved to the opened and closed positions.

10 A further object resides in so constructing the parts that adjustments can be made to vary the length of the injection period or interval, and consequently vary the content of the oil injection.

15 Still another object is to provide for fluid operation of the fuel inlet valve, to thus reduce the working load on the tripping mechanism to a minimum and avoid the possibility of slowing up or interfering with the parts 20 of the mechanism operating the trip.

25 With the above the other objects in view, which will be apparent to those skilled in the art, our present invention includes certain novel features of construction and combinations of parts which will be set forth in connection with the drawings.

In the drawings:

Figure 1 is a view in elevation of the control device from one side, with parts in section.

30 Figure 2 is a view in elevation taken substantially at right angles.

Figure 3 is a vertical sectional view through the control valve case.

35 Figure 4 is a sectional view taken substantially at right angles to the showing in Fig. 3.

40 Figure 5 is a fragmentary sectional view showing a modified type of injection period adjustment means.

Figure 6 is a diagrammatic view illustrating the method of variation of the injection period.

45 This device is adaptable for use in conjunction with a combined steam and Diesel engine of the type illustrated in our co-pending application, Serial No. 698,890, and to other types of Diesel engines and in connection with other mechanism requiring periodic oil or liquid injections, the main essential being that the engine or other mechanism be of the type having a reciprocating piston rod, valve rod, or other like part. In the present instance we have shown our device mounted in conjunction

with the bearing block 1 forming a guide for 55 the reciprocating stem 2, the stationary parts being mounted upon and carried by the bearing block.

A valve case 3, which is mounted at a suitable point has oil supply pipe 4 leading thereto and oil discharge pipe 5 leading therefrom to the injection valve of the Diesel engine or other point where the oil is needed. A fluid cylinder 6 is mounted at a point somewhat spaced from the valve case 3 and has the pipes 65 7 and 8 connected with opposite ends thereof for alternate supply of scavenging air, or other suitable fluid, under low pressure. At the remaining ends these pipes 7 and 8 are connected with a slide valve case 9, which 70 has inlet and outlet pipes 10 and 11 connected therewith. The inlet pipe is led from a tank, or other suitable source of supply for compressed air, or other fluid under low pressure, and the outlet or exhaust pipe 11 is extended 75 to the desired exhaust position.

Referring particularly to Fig. 3, the oil control valve is of a type adapted to be spring closed and to be opened by the rocker shaft 12. The case 3 has the oil supply and discharge pipes 4 and 5, opening thereinto at substantially right angles and the bore 13 is provided within the case substantially in line with the outlet passage through the discharge pipe 5 and the nipple 14 connecting the 85 same with the valve case. A valve seat member 15 is mounted adjacent the inner end of nipple 14 and a valve 16 is mounted for reciprocating movement within the bore 13 to close against the valve seat of member 15 to thus 90 close the discharge pipe. The remaining end of bore 13 is closed by a plug 17 having a central bore at its inner end to guide valve 16, and a coil spring 18 fitted around the valve stem bears between this plug 17 and the collar or flange 19 on the stem of the valve 16 to hold this valve normally closed against the seat. The rocker shaft 12 has a rocker portion 20 thereon adjacent the stem of valve 16 and this rocker portion is so formed that 100 as shaft 12 is given a partial revolution the rocker portion will engage with the collar or flange 19 and will raise the valve 16 from the seat 15, against the pressure of spring 18.

The fluid cylinder 6 has a piston 21 fitted 105 therein and the piston rod 22 extends through a suitable packing gland 23 at one end of the cylinder. A cross head 24 is provided on the

outer end of the piston rod 22 and travels in guide ways 25. An arm 26 loosely mounted on rocker shaft 12 is provided with an elongated slot 27 at its free end to slidably receive 5 a block pivoted on pin 28 carried by cross head 24, and as the piston 21 travels within cylinder 6 this arm or lever 26 will be oscillated. The rocker arm 29, secured on the rocker shaft 12, has adjusting bolts 30 and 10 31 to engage on opposite sides against the arm or lever 26, and this arm or lever is thus adjustably locked in conjunction with rocker shaft 12. A rocker arm 32 is fixed in conjunction with arm 29 to extend on the opposite side.

A slide valve 33 mounted within the case 9 is adapted to control the fluid supply and exhaust to and from cylinder 6, and this slide valve has a stem 34 extending from the case 20 and provided adjacent its free end with a bearing 35. A cross link 36 is pivoted in its middle portion in the bearing 35 and has one end extended to be substantially in line with the rocking lever 32. A link 37 connects 25 this end of lever 32 with the outer end of rocking lever 36 and this lever 36 is normally moved, by spring 38, to substantially the position shown in Fig. 1.

A tripping latch 39 is given swinging 30 mounting on a bearing carried by ring 40 secured on the stem 2, swinging movement of this latch being resiliently opposed by spring 41 and adjusting screw 42 being provided to adjust the angle at which the projecting end 35 of the latch extends from the stem 2.

A bearing portion 43 is carried on the bearing block 1 and adjusting member 44 is given sliding mounting therein for movement toward and away from the stem 2. At its outer 40 end this adjusting member is provided with a steep-pitched thread as indicated at 45, and an internally threaded collar 46 is revolvably carried by the bearing portion 43 to move adjusting member 44 endwise as this collar 45 is turned through the medium of handle 47. Adjusting member 44 has a bearing pin 48 at its inner end and a trip finger 49 is pivotally mounted on this pin 48. The trip finger 49 is connected with the free end of rocking 50 lever 36 through a link 50, this link being adjustable as to its length, through adjusting sleeve 51.

In Figure 5 we have illustrated a slightly modified form of injection period adjusting 55 mechanisms. The adjusting member 52 is fitted within a sleeve 53, and adjusting nut 54 is swiveled in conjunction with this sleeve and is fitted upon the steep-pitched thread 55 so that as handle 56 is swung the adjusting 60 member 52 will be moved endwise through sleeve 53. Sleeve 53 is externally threaded on a steep pitch and is keyed for endwise sliding movement in bearing 57. Adjusting nut 58 is swiveled in the bearing 57 and fits 65 the threaded portion of sleeve 53. Operating

handle 59 is provided on nut 58 and this operating handle can be connected with mechanically operated levers or with other mechanism by which the nut will be automatically turned to move adjusting member 55 70 and adjust the injection interval to suit different requirements of operation.

As diagrammatically shown in Figure 6, the full and dotted line positions of the latch member 39 are the normal extremes of movement, and as the bearing pin 48 is adjusted forward and back, to different points between "out" and "full," it will be appreciated that the trip finger 49 will fall from latch member 39 at different points as indicated on the vertical scale. At different points of elevation the period of injection will be lengthened or shortened, and the cubical contents of the oil injection will be varied substantially as indicated by the scale.

While we have herein shown and described certain specific embodiments of our invention and have suggested only certain possible modifications, it will be appreciated that changes and variations can be made to satisfy different requirements of use, without departing 80 from the spirit and scope of this invention.

We claim:

1. An oil injection control device comprising a control valve, fluid actuated valve operating means, and a trip operated control for the fluid actuated means.

2. An oil injection control device comprising a normally closed control valve, valve opening means, fluid actuated means associated with the valve opening means to operate the same, a fluid valve, and trip means controlling the operation of the fluid valve.

3. An oil injection control device comprising a control valve, fluid actuated valve operating means trip actuated means controlling the fluid actuated means, and means to adjust the trip means to vary the period of injection.

4. An oil injection control device for use with a mechanism having a reciprocating part comprising a control valve, fluid actuated valve operating means a trip latch carried by the reciprocating part, a trip finger to be engaged by the trip latch to render operative the fluid actuated means for the period of injection, and means to adjust the position of the trip finger to vary the length of the injection period.

5. An oil injection control device comprising a control valve, fluid actuated means to move the control valve to the open position, a fluid control valve governing the operation of the fluid actuated means, and adjustable trip means to determine the operation of the fluid control valve.

6. An oil injection control device comprising an oil supply line, a control valve in said line normally closed, a fluid cylinder, a piston in said cylinder connected to move said valve to an open position, a fluid control valve, trip

actuated means operating the control valve, and means to adjust the trip operated means.

7. In combination with a fluid actuated mechanism having a reciprocating part, a trip latch on the reciprocating part, a fluid control valve given stationary mounting, trip control means actuating the control valve, and a trip finger mounted in position to be engaged by the trip latch as the moving part reciprocates.

8. In combination with a fluid actuated mechanism having a reciprocating part, a trip latch on the reciprocating part, a fluid control valve given stationary mounting, trip control means actuating the control valve, a trip finger mounted in position to be engaged by the trip latch as the moving part reciprocates, and means to adjust the position of the trip finger with relation to the trip latch.

9. In combination with a mechanism having a reciprocating part, a trip latch carried by the reciprocating part, an oil supply line, an oil control valve in said line normally closed, a fluid cylinder, a piston mounted for

reciprocation in said cylinder, a connection 25 from said piston to open the control valve, a fluid supply to the fluid cylinder, a fluid control valve in the supply, trip operated means actuating the fluid control valve, and a trip finger in position to be engaged by the trip 30 latch.

10. In combination with a mechanism having a reciprocating part, a trip latch carried by the reciprocating part, an oil supply line, an oil control valve in said line normally 35 closed, a fluid cylinder, a piston mounted for reciprocation in said cylinder, a connection from said piston to open the control valve, a fluid supply to the fluid cylinder, a fluid control valve in the supply, trip operated means actuating the fluid control valve, 40 a trip finger in position to be engaged by the trip latch, and means to adjust the position of the trip finger with respect to the trip latch.

In testimony whereof we hereunto affix our 45 signatures.

WILLIAM GRISCOM COXE.
GUSTAV M. LAGERGREN.
